WHEELED SUITCASE

Grace H. McIntyre and Malcolm McIntyre,
Riverside, Conn.

Application March 5, 1949, Serial No. 79,848

1 Claim. (Cl. 280—38)

1
This invention relates to luggage of the type having wheels or casters thereon which enable the luggage to be easily moved about without carrying its full weight.

Though there have been several types of wheeled luggage suggested in the past, none of these became successful items of manufacture. One of the difficulties inherent in these known forms of wheeled luggage was that they were awkward in movement, and required considerable attention to steer them around and great annoyance, or even physical injury, when they encounter obstacles such as ridges, tracks or holes in a floor or pavement, or small articles lying thereon. Other difficulties in such devices are inherent cost and inefficiencies in retractable wheel devices and bulkiness, general ungainliness, and unsightly appearance.

An object of this invention is to provide improved rollable luggage.

A major object of this invention is to provide wheel assemblies for luggage and the like of such a character that the luggage can be towed along without requiring conscious effort to steer it.

Another object is to provide wheeled luggage which is easily and naturally lifted over obstructions, and is easily shifted from rolling to normal carrying and back.

It is a further object of this invention to provide wheel assemblies on luggage of such a character that the wheels have inherent stability as to direction of rolling and yet enable the direction of movement of said luggage to be changed with ease.

A further object of this invention is to provide dirigible wheel assemblies as described in the preceding objects that do not protrude objectionably beyond the adjacent face of the luggage when it is being carried in the normal manner and yet take up little space within the luggage.

A still further object of this invention is to provide dirigible wheel assemblies of the type as described that are compact, retractible, and yet sturdy and reliable in operation.

Other objects will in part be pointed out in the following specification of our invention and will in part become apparent therefrom.

By providing both a wheel on a fixed axle to the rear of the gravitational axis (i. e. the vertical axis through the center of gravity of the luggage) and a caster (i. e. a wheel on an axle swingable about an axis which extends upward and to a distance from the meridian through the center of the axle whether parallel to and spaced from the meridian or tilted from it) in front of

2
the gravitational axis and then pulling the luggage along by a handle on the side opposite these wheels, with the fixed wheel to the rear, the caster enables the luggage to be easily and naturally steered around turns without conscious thought or effort. The fixed rear wheel (or several wheels, if mounted close to a common transverse axis) causes the rear of the luggage to follow the fore wheel or wheels (i. e., the caster), and resist sidewise motion so as to allow "parking" the luggage by leaning it against a wall etc. In referring to a "fixed" wheel it is not, of course, meant that it does not rotate, but that its axis of rotation remains fixed, during operation, with respect to the fore-and-aft axis of the luggage and substantially perpendicular to it.

Although I have shown in these drawings and described in the following description, a preferred embodiment of our invention and have suggested 20 various modifications thereof, it is to be understood that these are not intended to be exhaustive nor limiting of the invention, but on the contrary, are given for purposes of illustration in order that others skilled in the art may fully 25 understand the invention and the principles thereof and the manner of applying the same in practical use and may be enabled to modify and adapt it in various forms, each as may be best suited to the conditions of a particular use.

30 Figure 1 is a side view of a piece of luggage, embodying the invention, shown in use;

Figure 2 is a side elevation of one embodiment 35 of this invention with the wheel and caster assembly in operative position, and the upper part of the luggage broken away;

Figure 3 is a bottom view of the device shown in Figure 2;

Figures 4 and 5 are sectional views taken on 40 the line 4—4 in Figure 3, showing the wheels extended for use and retracted, respectively;

Figure 6 is a side sectional view of the caster assembly shown in Figure 5;

Figure 7 is a bottom view of a second embodiment of this invention.

45 Figure 8 is a sectional view taken on line 8—8 in Figure 7 with the wheel housings partially in section;

Figure 9 is an isometric view of the interior of 50 a piece of luggage of Figures 7 and 8, open and partly broken away to show the wheel housings in the corners;

Figure 10 is a sectional view of a latch assembly used in either the first or the second embodiment;

Figure 11 is a fragmentary sectional view of a third embodiment of this invention;

Figure 12 is a bottom view of the embodiment shown in Figure 11;

Figure 13 is a view in side elevation of a suitcase case with a removable roller gear embodying the invention;

Figure 14 is a fragmentary sectional view, taken on line 14—14 of Figure 13 of a novel caster assembly shown in Figure 13;

Figure 15 is a fragmentary view taken on line 15—15 of Figure 13;

Figure 16 is a section on the line 16—16 of Figure 13; and,

Figure 17 is a fragmentary view of a different adjustable handle with the lower part in section and the upper part in elevation.

In Figures 1 through 6 a fixed axis wheel assembly is shown generally at 20 in which the wheel is mounted rotatably about a fixed axis in a support 22 and a caster assembly shown generally at 24, in which one or more wheels are mounted on one or more axes in a swivel support or supports 25, free to swivel about one or more axes upwardly directed in a plane perpendicular to the axis of the wheel. These assemblies 20 and 24, respectively, are shown mounted on hinge plates 26 and 28, hinged at or near the edges of openings 30, 31 respectively, in the end wall 32 of the suitcase 34 or other article of luggage.

The caster assembly 24 as shown here is of the conventional type (best shown in Figure 4) having a ball bearing 36 associated with a fork-type swivel support 25 for the caster wheel and a caster base 28. The details of the caster design, and particularly the ball bearing 36, of course are not essential, but facilitate the swiveling of the casters.

The pivots 38, 39 of the hinge members 26, 28 enable both the wheel assembly 20 and the caster assembly 24, when not in use, to be folded into their respective ends 30, 31 of a housing recess, as is shown in Figure 5. Any convenient locking device may be used to hold these assemblies in either position. As shown in Figure 6, this takes the form of a spring 40 engaging a cam or latch member 42. Another suitable device as shown in Figure 10 is a simple spring catch 40a mounted on the housing to engage the hinge member 28a at the edge of an opening 31a, the parts designated by the suffix "a" corresponding in function to the correspondingly numbered parts of Figures 1 to 6 inclusive. The hinge in this case is of the spring type, urged toward the open, extended position, and is held against such urging by the latch 40a when closed.

Again referring to Figures 1 to 6 inclusive, a handle 44 is secured to the small end wall 46 of the suitcase opposite that on which the wheel and caster assemblies are mounted. This handle enables the suitcase to be easily pulled forward and laterally and thus it guides the rolling on said wheel and caster assemblies. It is also adapted, and at a height convenient, for lifting the suitcase; so that if an obstacle is encountered, the natural reaction of an increased pull on the handle will have the required effect of picking up the suitcase until it is over the obstruction.

Advantageously, this handle is resistant against swinging from side to side, so that a lateral force applied to it will be transmitted to the luggage; but advantageously also it can be swung down against the end of the luggage so as to save space when not in use. To this end, the handle 44 is of molded plastic with squared clip enter-

ing ends and the clips 45 by which it is secured to the suitcase are of spring brass strip with enough of a "bow" at the corners to allow the handle ends to turn therein and swing down with a sufficient lateral push, but stiff enough to require more of a push than would ever be necessary in guiding the suitcase.

As shown in Figure 1, the caster assembly 24 precedes the wheel assembly 20 in the direction in which the suitcase is moved. In operation it will be found that a suitcase so equipped and used will follow one around corners as well as over obstacles, without any conscious attention on one's part; because the natural reaction of pulling the handle toward one, when the luggage tends to diverge, actually steers the caster so as to correct the divergence. Other types of casters such as are shown for example in Figures 13-16 can be used. In every such case, when the luggage tends to diverge, the natural pull on the handle, by swinging or tilting guides the front back toward the user. As the luggage moves over toward the user, it comes again under the handle, thus correcting any tilting caused by the lateral pull, so that it again moves straight forward. Conversely, if the luggage creeps too close to the user the natural push and outward tilting causes the wheels to be guided away from the user until the luggage comes into the natural and comfortable position under the user's hand. With any of the caster devices here shown, the weight of the luggage exerted on the swivel when the luggage is tilted swivels it so as to guide it toward the direction of tilting.

To assure that the caster will be thus at the front when the luggage is being rolled, it is put in a front portion of the end, i. e., adjacent the side which has the ordinary carrying handle (as clearly shown in Figures 1 and 13). When the suitcase is being lifted down from a rack or a platform or is set down on the floor or ground, habit dictates that the ordinary handle on the long, narrow (front) side be used. When it is desired to roll the luggage, it is most natural to pick it up by that handle and then reach over with the other hand to grasp the handle 44 on the end. This naturally leaves the side with the ordinary handle at the front and assures proper action of the caster.

In the embodiment shown in Figures 7-9 the retractable wheel and caster assemblies 20a and 24a have the pivots 38a and 39a of their hinge members 26a, 28a, mounted with their axes parallel to the principal direction of movement of the suitcase. This makes a somewhat more sturdy construction and also permits the receptacles 30a, 31a to be located in the corners of the suitcase 34a where they least interfere with its packing, see Figure 9.

This lateral hinge arrangement allows the wheels to be folded into the corners and yet when swung out for use, as shown in Figure 7, to be positioned substantially along the central plane of the luggage. A spring 50 in each hinge serves to hold the hinge plates 26a, 28a in their open positions as shown in Figure 7. The slots 52 are provided to receive spring latches 40a to hold the hinge against the spring pressure when the wheels are retracted.

If retractable wheel and caster assemblies are not used, but instead, as in Figures 11 and 12 the caster assembly 24b and wheel assembly 20b are rigidly mounted in recessed housings 31b and 30b respectively, the caster housing 31b must be large enough to allow the caster to swivel freely

about the pivotal axis of its mounting. The housing 31b as shown is a flanged cup approximating in its form the surface of revolution described by swivelling of the caster, but having clearance therefrom sufficient to allow free swivelling. Such clearance is advantageously not greater than about the spacing of the swivel axis from the meridian (i. e., the vertical axis) through the center of the wheel. With this embodiment the suitcase will stand on the wheels because it does not tilt beyond its limit of stability when the side edge contacts the ground.

The housing for the rear wheel can be even more economical of space and serves moreover as the wheel support with the wheel rotatably secured to an axle 56 mounted in this housing, or even directly to pivots formed in the housing itself.

In the embodiment of Figures 11 and 12, the housing cup 31b is formed so that it also provides a ball race for the ball bearing 36b of the caster swivel and the edge of the lower ball race is extended to engage a felt dust washer 54 which retains lubricant in the bearing and excludes dust and grit therefrom. The flange 55 as shown provides means for mounting the assembly in the wall of the suitcase.

This arrangement takes the least space from the interior of the luggage and has the virtue that it is always ready for immediate use, but it cannot be wholly hidden as in the case of the other embodiments described above.

This invention is also applicable to standard luggage and to miscellaneous articles and packages by embodying it in a removably attachable device as is represented by Figures 13 and 16. As shown the caster assembly 24c (of a novel type), is mounted on a toe piece 58 constituting a part of an articulate frame. For the most part this frame is flat but at the front a portion 59 is turned up to engage the edge of the luggage 34c. At the rear corners are heel members 60L and 60r also constituting portions of the frame and each of these have turned up portions 61 and 62 to engage the sides and back, respectively, of the luggage 34c.

Each of the heel members 60 carries a fixed wheel assembly 20c; and, due to the positioning of the heel members on the rear face of the suitcase, these fixed wheels have their axes of rotation perpendicular to the fore-and-aft axis of the suitcase and approximately in line with each other.

In this embodiment, as in the others, as many fixed wheels as desired may be used so long as they are thus mounted close to a common axis of rotation so that, as the casters swing the luggage, the fixed wheels can roll along concentric arcuate paths, and so that the several wheels do not interfere with tilting the luggage for steering as above described. One fixed wheel has advantage over more in that it is wholly versatile to swing the luggage around to any angle as well as along an arc of longer radius. The number of casters which can be used is limited only by cost, convenience and space to locate them and their location is unlimited except that at least one should be under, or forward with respect to, the handle; while the fixed wheel should be behind it.

A strap 64 is secured at one end to each heel piece 60 (as best shown in Figure 16) and is carried through a fair lead 66 on the opposite heel plate. One of these straps carries a buckle or other fastening means; and one passes through the handle 44c so as to hold it in place on the

suitcase 34c and transmit the necessary forces for guiding, pulling and/or lifting it. The lateral pull exerted on each heel plate by the strap attached to it, the turned up edge 61 which engages the suitcase to resist such pull, and the upward pull exerted by the other strap wrapped over the heel plate and through its fairlead 66 combine to hold these heel plates positioned at the corners of the luggage.

Likewise, each heel plate has attached to its front edge a strap 70 which extends to the toe plate 58 over a pulley or stanchion 72 and thence around the sides of the suitcase and through the handle with their ends buckled or otherwise pulled tight and secured as shown in Figure 13. A smooth twist in the strap allows it to pass smoothly over the stanchions or pulleys 72. The pull of these straps between the heel plates 60 and the toe plate 58 against their turned up edges 61 and 62 holds them tightly positioned against the corners of the suitcase; while the upward pull holds the toe plate positioned both laterally and vertically on the bottom end of the suitcase; and their connection with the handle transmits the necessary pull for guiding, pulling and lifting the suitcase.

Since the straps are adjustable and allow adjustment of spacing between the several portions of the articulate frame 58, 60r, 60L, this device is adapted for use on any luggage within the capacity of the straps to embrace.

The casters 24c shown in this embodiment of Figures 13, 14, 16, are of a novel type; but that type is not tied to the particular embodiment. It can be used directly secured to the suitcase or other luggage or to hinge plates 28; and other types of casters may be used instead on the toe plate of Figures 13, 16.

As best shown in Figure 14, a shaft 76 is mounted in bearings 78 secured to plate 58. Rocker arms 80 are individually mounted on the shaft; and between them on the shaft 76 is a spring 82 the ends of which engage arms 80 and urge them downward, while a center loop projects to engage and anchor on the plate 58. On the outer ends of arms 80 is mounted in universal (self-aligned) bearings an axle shaft 84 and on this shaft is carried the caster wheels.

In the case shown, the wheels are loosely mounted on the axis shaft 84 and held apart by spacers 86 and 88, but obviously this is not essential. The wheels could be rigidly and permanently secured to the shaft in the relation shown, and the shaft rotate in bearings (preferably ball bearings capable of accommodating the angular motion) in the arms 80.

So long as the suitcase is held upright, both arms 80 are swung down to the same extent against the resistance of spring 82; and axle 84 is perpendicular to the longitudinal axis of the suitcase; but when the suitcase is tilted to one side or the other, one arm is relaxed and extended farther, while the other is further compressed toward the bottom of the suitcase, with the result that the axle is turned and the wheels guided for steering the suitcase toward the direction of leaning. As it is thus moved under the handle it is restored to an upright position which brings the wheels back straight.

The handle as shown in Figures 13 and 15 is designed to give rigidity to forward and sidewise forces, and yet be adjustable as to height. This is accomplished by the links 88 pivoted in the grip member 86 and on the ears of the handle clip 45c. The bottom of each link 88 is radially ser-

rated and engages a similarly serrated block 89 on each side which is brazed or otherwise secured to the clip 45c. The bolt 90 when tightened locks the serrations together, but when it is released the links 88 can be swung up or down to raise or lower the handle to the most convenient height; or, if desired, handles with different length upright or link portions may be substituted, with or without the swinging adjustment.

Although Figures 13-16 show an embodiment utilizing a plurality of fixed wheels and likewise a plurality of casters may be used, there is important advantages in the use of only two wheels, a caster forward and a fixed wheel aft along the center of the lower end of the luggage.

As shown in Figure 1, the length of the suitcase plus the extension of the handle at one end plus the extension of the wheel 20 and caster 24 at the other end equals the height of a man's knuckles above the ground when he is walking with his elbow slightly flexed. This permits the most relaxed and comfortable handling of the luggage and leaves ample scope for movement of his arm to pick up the case when necessary to mount stairs or a curb or to pass over an obstruction. I have found surprisingly little variation in this height of a person's knuckles. Taller people in general have longer arms so that the height of the knuckles varies much less than their total height, and, moreover, so long as the handle is below the level of the elbow, one can tolerate a considerable difference in the extent to which the elbow is flexed without discomfort in walking with the luggage and without seriously impairing the ability to lift the luggage when necessary. The handle one the end of the luggage may be made adjustable to give the most comfortable position for each user. This is illustrated in Figures 13, 15 and 17.

In Figure 17 is shown a handle made of a double thickness of leather with a stiffening spring 92 between. The two ends of the handle are as shown in Figure 17 with a conventional grip portion between. The strap as shown is flexed to a smooth bend over the clip 45d which has its upper portion correspondingly curved. Its outer end is held against the suitcase by the resilient force of spring 92. A pin 94 secured on

the clip 45d engages in any of the holes 95; and by lifting up the end of the strap it can be released from pin 94 so as to slide it through the clip 45d and thus adjust the handle height.

5 We claim:

An article of luggage defined by an opposite pair of faces of large surface area, an opposite pair of faces of small surface area and an opposite pair of faces of intermediate surface area, all 10 of said faces being substantially rectangular, one of said intermediate faces being the top face of the luggage when carried, a carrying handle on said one intermediate face, a caster wheel and a fixed axis wheel on one of said small faces, a 15 carrying handle on the other of said small faces, said caster wheel lying between the center of the face to which it is attached and the plane of the intermediate face having the carrying handle thereon and the fixed axis wheel lying between 20 the center of the bottom of the face to which it is attached and the plane of the other intermediate face, said wheels constituting the only wheels on 25 said one small face and being disposed on that face midway between the planes of the large faces.
